UNITED STATES PATENT OFFICE

AZA LEROUX, OF NEW YORK, N. Y.

PICKPOCKETPROOF BUTTON

Application filed August 20, 1930. Serial No. 476,669.

This invention relates to alarm devices in general and particularly to a buttoning device adapted to cause an alarm when unauthorized persons try to pick a pocket of a garment.

One of the objects of this invention is to provide simple inexpensive pocket alarm means adapted to be readily associated to the interior of a pocket of a garment and having provisions for engaging the hole of a pocket flap and automatically turning it to a position at substantially right angles to the direction or plane of the buttonhole of the pocket.

Another object of my invention is to provide in connection with such device means for sounding an alarm when the buttonhole engaging means are operated.

Another object of this invention is to provide means whereby the button engaging device is automatically caused to assume a position at right angles to the plane of the pocket buttonhole.

Other objects and advantages of the invention will be hereinafter specifically pointed out, or will become apparent, as the specification proceeds.

With the above indicated objects in view, the invention resides in certain novel constructions and combinations and arrangement of parts, clearly described in the following specification and fully illustrated in the accompanying drawings, which latter show embodiments of the invention as at present preferred.

35 In said drawings:

Fig. 1 represents a portion of men's trousers provided with a buttonable pocket in which my device is secured.

Fig. 2 is an enlarged cross-sectional view 40 taken on line 2—2 of Fig. 1 and illustrating my device in greater detail.

Fig. 3 is a plane view partially in cross-section of my device as seen attached to the pocket lining; and

45 Fig. 4 is a perspective detail view of the knocker arrangement of my device.

Referring more specifically to the figures, numeral 10 denotes a portion of men's trousers provided with a pocket forming a pocket flap 11 associated at 12 with the garment.

Pocket flap 11 is preferably provided with a buttonhole 13 adapted to be engaged by the operating member of my device. The alarm is secured to the lining 14 of the pocket and is attached thereto by sewing.

55

The device itself consists of a base or attaching member 15 provided with a plurality of attaching holes 16, by means of which it is sewed on to lining 14 of the pocket. Extending upwards from base member 15 there will be seen separator pins 17 and 18 which support a bell 19, provided at its inner periphery with extensions 20, grouped within sectors so that portions of the inner bell periphery are smooth, while other portions of the periphery are roughened by these extensions, as clearly seen from Fig. 3.

60

Within the center of the bell there is journaled a pin or shaft 21 extending partially into the interior of the bell and partially projecting outwards thereof, which outer portion is provided with a handle 22 while the inner portion is enlarged at 23 and forms a support for a flexible knocker member 24 provided with balls at its end indicated at 25.

65

Secured to pin 17 and wound about enlarged portion 23 of shaft 21 and secured thereto with its other end there will be seen a coil spring 26, which is so arranged as to normally cause knocker 24 to assume a position in a plane at substantially right angles to that of the buttonhole 13. Handle 22 being disposed in the same direction, that is parallel to knocker 24, will assume a position in the same plane as the latter. Pin 17 not only serves for attaching means of spring 26 but also acts as a stop for knocker 24.

70

When handle 22 is turned in a clockwise direction as indicated by arrow I, knocker 24 will be stopped in its motion by supporting pin 18 in which position, indicated in broken lines in Fig. 3, the handle member 22 will be in the plane of buttonhole 13. In this position handle 22 may be disengaged from buttonhole 13 and therefore the pocket flap 11 may be opened.

75

In order to have handle 22 engage buttonhole 13, thereby closing pocket flap 11, it is necessary that handle 22 is brought into horizontal position. When it is released the

100

handle will assume its normal vertical position, thereby interlocking with the pocket hole.

In the event an unauthorized person should wish to pick the pocket, he has to turn handle 22 into horizontal position in line with buttonhole 13. This movement causes flexible knocker 24 to move over the two groups of extensions 20 of the bell periphery thereby creating a sound or a vibration sufficient to cause the wearer of the garment to realize that his pocket is being picked.

Needless to say that bell 19 is preferably spaced from base member 15 so as to produce an audible sound. However, ordinarily the cloth from which the garment is made will somewhat deaden the audible sound and the vibrations produced by the knocker passing over extensions 20 usually suffice to cause the desired alarm for which my device is designed.

The hereinbefore described construction admits of considerable modification without departing from the invention; therefore, it is the wish not to be limited to the precise arrangements shown and described, which are as aforesaid, by way of illustration merely. In other words the scope of protection contemplated is to be taken solely from the appended claims, interpreted as broadly as is consistent with the prior art.

What is claimed as new is:

1. The combination with a hole-equipped pocket of a garment, of a device for the purpose described, comprising a base or attaching member provided with means for securing it to the interior of a pocket, supporting pins extending from said member, a bell or sound member secured to said pins and distanced from said base member, a resilient bell actuating member in operative engagement with said bell and comprising a resilient bar or knocker operative within the bell and a pocket hole engaging handle extending beyond the bell, a spring connecting said actuating member with one of said pins and adapted to normally cause the positioning of said actuating member into one plane, while the latter may be swung, by means of said handle, into another plane when desired, said pins serving as limiting devices for the resilient bar or knocker.
2. The combination with a hole-equipped pocket of a garment, of a device as set forth in claim 1, said bell provided at its inner periphery with a plurality of projections, said bar or knocker provided with balls adapted to engage said projections when the bar is operated either by its handle or by said spring, thereby causing the sounding or vibration of the bell.
3. A pickpocket proof button adapted to be associated with the interior of a garment pocket provided with a buttonhole equipped flap, comprising a base provided with means

for attaching it, a pair of pins extending from the base, a bell secured to said pins and distanced from said base, a plurality of projections provided at the inner periphery of said bell, a knocker operatively associated with the latter and composed of a resilient member equipped with balls at its ends adapted to engage said bell projections, a shaft journaled with, and extending partially into and partially from said bell, said resilient member associated with the inner extension of said shaft, a handle associated with the outer extension of said bell shaft and adapted to engage the button hole of the pocket flap, a coil spring secured to one of the bell supporting pins at one end and to said shaft with its other end and adapted to cause said shaft to normally assume a position at which said knocker will stay in a plane at substantially right angles to the plane of the buttonhole, said handle, being parallel with said resilient member, assuming a similar position, said pins adapted to limit the movements of said resilient member within the bell, said handle adapted to facilitate the turning of said shaft, thereby actuating said resilient member, and further adapted to be thrust through and engage the buttonhole when turned into the plane of the latter and to assume its normal, right angular position in respect to the plane of the hole, when released, said resilient member adapted to pass with its ball ends over the internal projections of the bell while said handle is turning, thereby causing the bell to emit an alarm sound.

In testimony whereof I hereby affix my signature.

AZA LEROUX.
